John J. Keff
Letters Patent

7447X

The Schedule referred to in these Letters Patent, and making part of the same, containing a description in the words of the said John J. Keff himself of his improvement in the sieve or riddle called a Rotator for separating ashes from cinders or coal.

It consists of a circle of iron with a handle 411 divided in the middle by a bar having ribs or bars running transversely from it to the arch of the circle 4 made perfectly firm & fast - In the center upon the bar of the chord dividing the circle is a circular knob grooved on its under side with a smooth pyramidal cavity which circumvolutes upon an abrupt cone attached to another bar on which the rotator rests or vibrates when separating the coal & cinders of the grates from the ashes -

Upon this rotary movement I found my right of claim being new in the invention having never heretofore been applied or used for such purposes in stoves - the rest are upon the old principles -

Within the space of the other half of the circle, between the chord & the arch moves a smaller segment of a circle having quadrants at the extremities of its chord, which play into grooves on the surface of the circle of the rotator 411 supported in an horizontal position by an iron pin which slips thro a channel or groove cut underneath the handle of the rotator - When the pin is withdrawn the upper segment drops perpendicularly downward constantly emptying the grate of its contents -
